SET OF PLAYING CARDS

Rachael C. Davis, Lockridge, Iowa

Application January 25, 1949, Serial No. 474

Term of patent 14 years

(Cl. D34—13)

To all whom it may concern:

Be it known that I, Rachael C. Davis, a citizen of the United States, and a resident of Lockridge, in the county of Jefferson and State of Iowa, have invented a new, original, and ornamental Design for a Set of Playing Cards, of which the following is a specification, reference being had to the accompanying drawing, forming a part hereof.

Figures 1 to 14 are face views of the cards in the set of playing cards, showing my new design.

In the set of 53 cards there is one card as illustrated in Fig. 1 of the drawings; ten of Fig. 2; one of Fig. 3; one of Fig. 4; one of Fig. 5; one of Fig. 6; four of Fig. 7; ten of Fig. 8; one of Fig. 9; one of Fig. 10; one of Fig. 11; ten of Fig. 12; ten of Fig. 13 and one of Fig. 14.

The backs of the cards, which are the reverse of those shown, may be plain or printed in any conventional card back design.

I claim:

The ornamental design for a set of playing cards, as shown and described.

RACHAEL C. DAVIS.
